MAIL BOX

Alan W. Duncan, Itasca, and Joseph A. Burlini, Morton Grove, Ill., assignors to Sears, Roebuck and Co., Chicago, Ill., a corporation of New York

Filed Apr. 22, 1963, Ser. No. 74,545

Term of patent 14 years

(Cl. D74—9)

The figure on the drawing is a front-side perspective view of a mail box embodying our new design.

The top, bottom and back of the mail box are plain and the side not shown is similar to the side shown in the drawing except that it lacks the signal member and support for same; the back and side of the grill not shown in the drawing are similar to the front and side shown therein.

We claim:

The ornamental design for a mail box, as shown and described.
